UNITED STATES PATENT OFFICE.

WILLIAM HOWARD SMITH, OF ATLANTA, GEORGIA, ASSIGNOR TO AMERICAN CAN COMPANY, OF NEW YORK, N. Y., A CORPORATION OF NEW JERSEY.

ORCHARD-HEATER.

1,010,461.

Specification of Letters Patent.

Patented Dec. 5, 1911.

Application filed December 20, 1910. Serial No. 598,395.

To all whom it may concern:

Be it known that I, WILLIAM HOWARD SMITH, a citizen of the United States, residing in Atlanta, in the county of Fulton 5 and State of Georgia, have invented a new and useful Improvement in Orchard-Heaters, of which the following is a specification.

My invention relates to improvements in orchard heaters.

10 The object of my invention is to provide an orchard heater of a simple, efficient and durable construction capable of being manufactured and furnished at small cost, and which may be easily and quickly assembled, 15 filled with fuel and lighted.

My invention consists in the means I employ to practically accomplish this object or result as herein shown and described and more particularly specified in the claims; the 20 same comprising in coöperative combination a sheet metal pot or liquid fuel container having an external roll at its upper end; an annular sheet metal top secured thereto; a perforated sheet metal chimney or flue member coiled or curved into cylindrical shape 25 with its meeting edges overlapping and fitting within the opening of the annular top and resting at its lower end on the bottom of the pot or fuel container; a corrugated 30 sheet metal hood of frusto-conical shape, having an inwardly projecting annular flange at its upper end surrounding the upper end of the chimney or flue member, and with the inner walls of its corrugations at 35 the lower end surrounding and wedgingly engaging the upper end of the pot or fuel container and its annular top secured thereto, to form a series of air passages distributed uniformly around the whole circumference 40 of the pot or fuel container at the upper end thereof. The annular top is made of a square piece of sheet metal the side of which is less than the diameter of the upper end of the fuel container and the diagonal 45 of which exceeds said diameter, thus forming openings for air passages between the annular top and the upper rim of the container. A cover, preferably of a square piece of sheet metal with its corners turned at an 50 angle to fit in and engage corrugations of

the hood, is provided to cover the hood and flue of the heater when the heater is not in use and exclude rain.

My invention also consists in the novel constructions of parts and devices and in 55 the novel combinations of parts and devices herein shown and described and more particularly specified in the claims.

In the accompanying drawing forming a part of this specification Figure 1 is a side 60 elevation of an orchard heater or pot embodying my invention. Fig. 2 is a central vertical longitudinal section on line 2—2 of Fig. 1. Figs. 3 and 4 are horizontal sections on lines 3—3 and 4—4 respectively of Fig. 2. 65

In the drawing 1 represents the body of a sheet metal fuel pot or container preferably of frusto-conical form with its larger end uppermost and made like the other parts of ordinary black sheet iron or steel. The body 70 has one or more lock side seams 2 at the meeting edges of the blank or blanks from which it is formed and the bottom 3 is secured to the lower end of the body 1 by a double seam 4 so that all the seams of the 75 vessel will be liquid tight for holding crude petroleum or other like liquid or semi-liquid fuel and adapted to withstand the heat and fire. At its upper end the body of the vessel is provided with an external rolled rim 80 5 which embraces a stiffening wire 6.

The annular top 7 has a large central opening 8 to receive the chimney or flue member 9 and it is preferably furnished with segmental flanges 10 turned under the 85 external rolled rim 5 of the container to secure the annular top thereto while leaving openings or air passages 11 between the annular top and the rim of the container at the four rectangular sides of the annular 90 top, the segmental curved flanges 10 being formed at the diagonal rounded portions of the square sheet from which the annular top is formed.

The chimney or flue 9 is furnished with 95 a series of openings or perforations 12 extending from end to end and all around the circumference. The chimney or flue member 9 is preferably formed by coiling or curving a rectangular piece of perforated 100

sheet metal into cylindrical form, its meeting edges 13, 14, being loose or unconnected but overlapping each other. The chimney or flue member 9 is open at both ends and 5 fits removably within the central opening of the annular top and rests at its lower end against the bottom 3 of the fuel container 1.

The sheet metal hood 15 is of frusto-conical shape with its smaller end uppermost 10 and it is provided with a series of vertically or longitudinally extending corrugations 16 which taper in width from the upper to the lower end of the hood, the corrugations being materially deeper at the lower end of the 15 hood than at the upper end thereof. The inner walls 17 of the corrugations 16 wedgingly engage the rim 5 of the container 1 and segmental flanges 10 of the annular top which embraces the rolled rim of the container 20 for a portion of its circumference. This wedging engagement between the lower end of the corrugated hood and the upper end of the container 1 serves to securely hold the hood 15 in place on the container. The 25 externally projecting walls 18 of the series of corrugations 16 form a series of air passages or openings between the rim of the container 1 and the hood to admit air into the container through the openings 11 between the top 7 and container 1 and through the perforations 12 in the flue 9, which are both above and below the annular top 7, to support combustion of the fuel in the container and create a proper draft in the flue 30 9. The corrugated hood 15 is provided at its upper end with an inwardly projecting annular flange 19 which surrounds the upper end of the cylindrical chimney or flue member 9. The hood is also provided with an 35 upwardly projecting annular bead 20 at the junction of the longitudinal corrugations 16 with the annular horizontally extending flange 19. As the corrugated hood has a tight wedging engagement at its lower end 40 with the upper end or rim of the fuel container the hood will be held firmly in position.

The cover 21 which covers the upper end of the flue or chimney piece 9 and of the 45 hood 15 when the vessel is not in use or which may be partly removed to regulate combustion as desired, may be of any suitable form, such for example as a flat piece of metal, a round disk with a depending annular flange or a rectangular piece of metal with its corners 22 turned at an angle to engage the corrugations 16 of the hood 15.

In operation the body or container 1 is filled with crude petroleum or other cheap 50 liquid or semi-liquid fuel and then ignited, preferably by a torch or by putting a small quantity of waste or other fibrous material in the container through the flue. The air

to support combustion enters under the hood and passes in part beneath the top plate through the openings 11 between its side edges and the rim of the container and thence passes through the holes or perforations in the flue member into the flue chamber, combustion being confined or chiefly confined to the surface of the oil inside the flue. As the oil in the container is consumed, further holes in the opening are exposed for passage of air therethrough. The air entering under the hood in part passes into the flue through the holes therein above the top plate, thus providing adequate draft and insuring a more perfect consumption of the fuel.

I claim:

1. An orchard heater, comprising in combination a sheet metal fuel container having an externally rolled rim at its upper end, a top plate secured thereto and having openings between its side edges and the rim of the container, and provided with a central opening, a perforated flue sheet rolled into a cylindrical form with loosely overlapping edges, and fitting within the central opening of said top plate, and resting at its lower end on the bottom of the container, and a frusto conical longitudinally corrugated hood with the inner walls of its corrugations wedgingly engaging the outer rim of the container top plate, the outer walls of its corrugations forming a series of air passages distributed entirely around the circumference of the container, said hood having an inwardly projecting annular flange at its upper end surrounding the upper end of the flue, said flange of the hood being substantially flush with the upper end of the flue with an annular air passage therebetween and serving to deflect air inwardly over the upper end of the flue and a common cover plate adapted to close both the upper end of the hood and the upper end of the flue, said cover having downwardly bent and circumferentially arranged engaging fingers, substantially as specified.

2. An orchard heater, comprising in combination a sheet metal fuel container having an externally rolled rim at its upper end, a top plate secured thereto and having openings between its side edges and the rim of the container, and provided with a central opening, a perforated flue sheet rolled into cylindrical form with loosely overlapping edges, and fitting within the central opening of said top plate, and resting at its lower end on the bottom of the container, and a frusto conical longitudinally corrugated hood with the inner walls of its corrugations wedgingly engaging the outer rim of the container top plate, the outer walls of its corrugations forming a series of air passages distributed

entirely around the circumference of the container, said hood having an inwardly projecting annular flange at its upper end surrounding the upper end of the flue, said flange of the hood being substantially flush with the upper end of the flue with an annular air passage therebetween and serving to deflect air inwardly from the upper end of the flue, substantially as specified.

WILLIAM HOWARD SMITH.
